UNITED STATES PATENT OFFICE.

WALTER L. KEEFER, OF CHAMBERSBURG, PENNSYLVANIA.

BRUSH MOUNTING FOR VACUUM CLEANERS.

Application filed June 18, 1925. Serial No. 38,040.

My invention relates to improvements in vacuum cleaners and has reference more particularly to those in which a rotary brush is mounted in a horizontally elongated suction nozzle and is driven by a pair of supporting wheels at the ends of said nozzle, the principal object of the invention being to provide a new and improved mounting means which enables the brush to be vertically adjusted to any desired extent and also permits easy removal of said brush from the nozzle when desired.

With the foregoing in view, the invention resides in the novel subject matter herein-
15 after described and claimed, the description being supplemented by the accompanying drawing.

Figure 1 is a partial bottom plan view of a suction nozzle provided with the improved
20 brush mounting means.

Figure 2 is a vertical sectional view as indicated by line 2—2 of Fig. 1.

Figure 3 is a vertical sectional view cut in a plane parallel with but spaced from the
25 plane on which Fig. 2 is cut.

Figures 4 and 5 are respectively a side elevation and an edge view of one of the bearing arms which support the brush.

In the drawing above briefly described,
30 the numeral 1 designates a horizontally elongated suction nozzle provided with a rearwardly projecting neck 2 and formed with rearward extensions 3 at its ends, in which rubber tired supporting wheels 4 are mounted upon appropriate axles 5.

Extending longitudinally within the nozzle 1, is a brush 6 having friction wheels 7 at its ends contacting with the rubber tires of the wheels 4, so that these wheels rotate
40 the brush as the cleaner is moved over the floor. The ends of the brush are provided with trunnions 8 which are rotatably supported in a manner hereinafter described.

Extending longitudinally in the suction
45 nozzle 1, above the brush 6, is a metal strip 9 whose front and rear edge portions are preferably stamped to give them an arched formation 10, so as to effectively reinforce the strip against bending. The ends of this
50 strip are bent vertically downward as indicated at 11 and these downturned strip ends are provided with integral, rearwardly projecting arms 12 whose free ends are pivotally supported by the axles 5. Vertical
55 bearing arms 13, preferably formed of compressed fibre, are disposed at the inner sides

of the downturned strip ends 11, the upper ends of said arms 13 being connected with said strip ends, by appropriate pivots 14, while the lower ends of said arms 13 are formed with rearwardly facing notches 16 which rotatably receive the trunnions 8. The side portions of the arms 13, adjacent the strip ends 11, are cut away as at 17, near the upper ends of said arms, leaving oblique shoulders 18 at the lower ends of the cut away portions and exposing parts of the pivots 14 at these cut away portions. Coiled around these exposed parts of the pivots 14, are wire springs 19 having lateral ends 20 and 21 respectively which engage the strip 9 and the arms 13. The arms 20 may either contact with the shoulders 18 or may have their terminals laterally directed and hooked around the front edges of the arms 13.

The springs 19 exert a constant rearward force on the arms 13, to hold the friction wheels 7 of the brush 6 against the rubber tires of the supporting wheels 4, and if these tires pick up any foreign matter from the floor, the arms 13 and the brush may readily yield forwardly to allow such foreign matter to pass without interfering with rotation of the brush or the supporting wheels.
80 Moreover, when the arms 13 are forwardly
85 swung to the desired extent, the entire brush may be removed from the nozzle. Then, to prevent excessive movement of the arms 13 under the influence of the springs 19, I provide stops 22 which are preferably stamped
90 inwardly from the downturned ends 11 of the strip 9, said stops being disposed opposite the notched edges of the arms 13.

Secured by rivets or the like 23 to the central portion of the strip 9, is a curved spring 95 arm 24 whose lower end is provided with a detent 25 and with a finger-piece 26, said detent being co-operable with vertically spaced teeth 27 formed on the inner side of the front wall, of the nozzle 1. By swinging the arm 24 rearwardly, by means of the finger-piece 26, the entire brush mounting means may be vertically swung to adjust the brush to any desired position, so that it will exert the desired pressure upon rugs or the like, or will entirely clear them, as occasion may demand. Moreover, by releasing the detent 25 from the teeth 27 and pulling downwardly upon the finger-piece 26, the brush mounting means is downwardly swung out 110 of the nozzle about the axles 5 as pivots. Then, it is an easy matter to swing the

arms 13 out of engagement with the trunnions 8, permitting the brush to be readily removed. After removal of this brush and release of the arms 13, the stops 22 function to prevent said arms from moving excessively under the influence of the springs 19, so that no difficulties will be encountered when it is desired to reengage the brush with the supporting means.

10. It will be seen from the foregoing that I have provided an exceptionally simple and inexpensive, yet a very desirable means for adjustably mounting the brush in the suction nozzle, and as excellent results are obtainable from the details disclosed, they are preferably followed. However, within the scope of the invention as claimed, modifications may be made.

In conclusion, it may be added that while 20 Fig. 1 discloses only one end portion of the suction nozzle and associated parts, the construction relating to the other end thereof is the same, as will be readily understood without further illustration or explanation.

25. I claim:

1. In a vacuum cleaner, a horizontally elongated suction nozzle having supporting wheels at its ends, a brush extending longitudinally in said nozzle and driven by said 30 wheels, a metal strip extending longitudinally in the nozzle over said brush and having integral downturned ends provided with bearings for said brush, arms integral with and projecting horizontally from said 35 downturned strip ends, said arms being

pivotedly supported co-axially with said wheels, a curved spring arm secured to said strip and disposed at one side of the nozzle, the free end of said spring arm having a detent and a finger piece, and vertically spaced teeth on said one side of the nozzle co-operable with said detent in holding the strip and brush in different adjusted positions.

2. In a vacuum cleaner, a horizontally elongated suction nozzle having supporting wheels at its ends, a brush extending longitudinally in said nozzle and driven by said wheels, a metal strip extending longitudinally in the nozzle over said brush and having integral downturned ends, arms integral with and projecting horizontally from said downturned strip ends, said arms being pivotedly supported co-axially with said wheels, vertically disposed bearing arms having bearing notches near their lower ends facing said wheels and removably receiving the ends of the brush, pivots connecting the upper ends of said bearing arms to the inner sides of said downturned strip ends, springs coiled around said pivots and having ends engaged with the metal strip and the bearing arms respectively to hold the brush in driving engagement with the aforesaid wheels, and means for holding the aforesaid strip in different vertically adjusted positions in the nozzle.

In testimony whereof I have hereunto affixed my signature.

WALTER L. KEEFER.
